[57] **CLAIM**

The ornamental design for a television case, as shown and
described.

DESCRIPTION

FIG. 1 is a front elevational view of the television case of the
present invention;

FIG. 2 is a back elevational view of the television case of
FIG. 1;

FIG. 3 is a left side elevational view of the television case
of FIG. 1;

FIG. 4 is a right side elevational view of the television case
of FIG. 1;

FIG. 5 is a top plan view of the television case of FIG. 1;
and,

FIG. 6 is a bottom plan view of the television case of FIG.
1.

The cord shown in FIGS. 2 and 6 is fragmented for ease of
illustration and to indicate indeterminate length.
